UNITED STATES PATENT OFFICE.

TREMONT W. RICKEL, OF McALLEN, TEXAS.

WINDOW-SASH LOCK.

1,271,772.

Specification of Letters Patent.

Patented July 9, 1918.

Application filed October 15, 1917. Serial No. 196,711.

To all whom it may concern:

Be it known that TREMONT W. RICKEL, a citizen of the United States, residing at McAllen, in the county of Hidalgo and State of Texas, has invented certain new and useful Improvements in Window-Sash Locks; and he does hereby declare the following to be a full, clear, and exact description of the invention, such as will enable others skilled in the art to which it appertains to make and use the same, reference being had to the accompanying drawings; and to the letters and figures of reference marked thereon, which form a part of this specification:

This invention relates to new and useful improvements in sash locks and the object in view is to produce a simple and efficient device of this nature, and consists essentially in the provision of means for permitting either sash to be locked or one sash to be partially or fully opened, means being provided to cause both sash to be automatically locked when the sash are closed.

The invention consists of further details of construction, combinations and arrangements of parts which will be hereinafter fully described, shown in the accompanying drawings and then specifically defined in the appended claims.

The invention is illustrated in the accompanying drawings which, with the letters of reference marked thereon, form a part of this specification and in which:

Figure 1 is a perspective view showing the application of my invention to the upper and lower sash of a window.

Fig. 2 is an elevation, and

Fig. 3 is a sectional view on line 2—2 of Fig. 2 looking in the direction of the arrow.

Reference now being had to the details of the drawings by letter:

A designates the lower sash of a window and B is the upper sash. The lower sash has pivotally mounted upon the pin C a swinging member D, the upper portion of which is bent at a right angle and projects as at D² and extends over the top of the lower sash and also over a portion of the upper sash, as shown clearly in Fig. 1 of the drawings. Said member D has a handle D' projecting from the angled portion thereof and forms a convenient means for swinging the member. A bail-shaped strap E is fastened to the opposite edges of the rail of the lower sash and serves to limit the swing-

ing movement of the member D and also serves as a means for preventing any tampering with the member through the medium of an instrument from the outside of the window to cause the same to be thrown out of operative relation with the other parts of the apparatus.

A right angled plate F is fitted over the top of the lower sash over which the lateral projection D² of the member D has a play, said plate being provided for the purpose of protecting the sash against which said projection D² contacts when the member is swung to its limit in either direction.

A metallic plate H of the general shape shown in the drawings is fastened to the face of the upper sash and has its lower end H' bent at a right angle extending over a portion of the upper surface of the bottom rail of the upper sash, as shown clearly in Fig. 1 of the drawings. Said plate H has flanges I and K, formed upon its opposite edges, which at their lower ends terminate a slight distance above the angled flange H' at the bottom. Said plate, it will be noted, has its upper portion contracted and the flanges I and K curve to conform to the shape of the plate. A central partition L projects from said plate forming a left way N open at its upper end, and a right way M which, near its upper end, has a transverse partition J forming a stop against which the inner end of the projection D² of the member D is adapted to contact to limit the upper movement of the lower sash.

It will be noted upon reference to Fig. 2 of the drawings that the upper end of the inner partition L is bent at an inclination as at O for the purpose of guiding the end of the extended portion D² into the way N when the lower sash, after having been raised to its upper limit, is closed.

A spring T is fastened at its upper end to the face of the plate H and its lower end is free, the said partition L projecting over the spring a slight distance, as shown clearly in Figs. 1 and 2 of the drawings. Inclined members S project from the plate and are positioned in front of said spring and are provided for the purpose of throwing the member D to an upright position after the lower sash has been raised and returned to its starting position. The lower free end of the spring serves as a stop to prevent the lower sash being raised when the member D is in a vertical position.

In operation, when the member D is in the position shown in Figs. 1 and 2 of the drawings, the sash will be locked. If any attempt is made to raise the lower sash or 5 lower the upper sash, the inner end of the projection D² will come in contact with the lower end of the spring. If it is desired to raise the sash part way, the member D is swung to the right, so that when the lower 10 sash is raised the end of the projection D² will pass up through the right way M a distance limited by the partition J at the upper end of the way M. As the lower sash is raised the end of the projection D² coming 15 against the flange K will cause the member D to swing toward the vertical portion so that on the closing of the lower sash the inner end D² of the member D will come in contact with the right hand guide member S, and as the lower sash approaches its 20 closed position said member D will return to a locked position, as shown in Fig. 2 of the drawings. Should it be desired to raise the lower sash its limit the member D is 25 swung to the left, so that when the lower sash is raised the projection D² will enter the left way N. When the lower sash is 30 closed, assuming that it has been raised to its upper limit, the projection D² coming in contact with the curved flange I or the inclined portion O of the middle flange, will cause 35 said member D to approach a vertical position, and as the lower sash approaches its closed position, the portion D² coming in contact with the left inclined guide way 40 S will cause the member D to assume the position shown in Fig. 2 and after the sash closes it will be automatically locked. Any attempt to raise the lower sash will be prevented by the portion D² coming in contact 45 with the spring. It will be noted that the member D should be held with sufficient friction at its lower end where it is pivoted to the frame of the sash, so that there will be no possibility of the member accidentally 50 swinging to the right or left by jar or some other causes, which would throw said member D in such a position that the sash might be raised.

50 What I claim to be new is:

1. An automatic window sash lock comprising in combination with the upper and lower sash of a window, a swinging member mounted upon one sash and a plate upon 55 the other, a central partition forming a right and a left way, a spring fastened at one end to the plate and coöperating with said member to hold the sash locked, and means for automatically moving said member so that it will assume a locked relation 60 with the spring when the sash are closed.

2. An automatic window sash lock comprising in combination with the upper and lower sash of a window, a swinging member 65 mounted upon one sash and a plate upon

the other, a central partition forming a right and a left way, a spring fastened at one end to the plate and coöperating with said member to hold the sash locked, said plate having marginal curved flanges de- 70 signed to cause said member to swing toward a vertical position when the sash is raised, and means projecting from the plate to swing the member to a vertical position as the sash is closed.

3. An automatic window sash lock comprising in combination with the upper and lower sash of a window, a swinging member mounted upon one sash and a plate upon the other, a central partition forming a 80 right and a left way, a spring fastened at one end to the plate and coöperating with said member to hold the sash locked, said plate having marginal curved flanges de- 85 signed to cause said member to swing toward a vertical position when the sash is raised, oppositely disposed inclined guide members projecting from said plate and ex- 90 tending over a portion of said spring and serving to throw the member to a vertical position as the sash is closed.

4. An automatic window sash lock comprising in combination with the upper and lower sash of a window, a swinging member pivoted to the lower sash, and having a 95 laterally extending portion projecting over the top of the lower sash and beyond the inner face of the latter, a plate secured to the face of the upper sash, said plate having side flanges upon the marginal edges there- 100 of, and a central partition forming a right and a left way, a spring fastened at its upper end to said plate and its lower end free and positioned over the inner end of the laterally extending portion of said member 105 when the latter is in a vertical position, the marginal flanges of the plate serving to cause said member to be tilted toward the vertical position as the lower sash is raised, and inclined guide members to further swing 110 the member to a vertical position as the lower sash reaches its closed position.

5. An automatic window sash lock comprising in combination with the upper and lower sash of a window, a swinging member 115 pivoted to the lower sash, and having a laterally extending portion projecting over the top of the lower sash and beyond the inner face of the latter, a plate secured to the face of the upper sash, said plate having 120 side flanges upon the marginal edges there- of, a central partition projecting from the plate and forming a right and left way, a transverse partition at the upper end of one of said ways against which the lateral pro- 125 jection of said member is adapted to contact to limit the opening movement of the lower sash, the marginal flange serving to swing said member to a vertical position as the lower sash is raised, and inclined guide 130

- members projecting from the plate to further throw said member to a vertical position, as the lower sash approaches its lowest position.
- 5 6. An automatic window sash lock comprising in combination with the upper and lower sash of a window, a swinging member pivoted at its lower end to the face of the lower sash and having a laterally projecting portion extending over the top of the lower sash and beyond the inner face thereof, said member having a handle, a plate secured to the upper sash and having inwardly inclined curved marginal flanges, a central vertical partition projecting from the plate, forming a right and a left way, and having its upper end laterally inclined, a transverse partition at the upper end of the right way, the marginal flanges of the plate tending to swing said member toward a vertical position as 20 the lower sash is raised, a spring fastened at its upper end to said plate and extending below the central partition, and inclined guide members projecting from the plate and extending over the free end of the 25 spring and serving to further swing said member to a vertical position as the lower sash closes.
